ANIMAL FEEDING APPARATUS

Arthur L. Williamson, 728 W. Main; and Fred T. Mason,
612 Plaza Drive, both of Moore, Okla. 73160; and
Jacky L. Dyer, Sr., Box 149, Yukon, Calif. 73099

Filed June 9, 1972, Ser. No. 261,575

Term of patent 14 years

Int. Cl. D30—03

U.S. Cl. D30—13

FIG. 1 is an end, top and side perspective view of an animal feeding apparatus, showing our new design;

FIG. 2 is a side elevational view, the opposite side being substantially a mirror image thereof;

FIG. 3 is an end elevational view, the opposite end being substantially a mirror image thereof; and

FIG. 4 is a bottom plan view thereof.

We claim:

The ornamental design for an animal feeding apparatus, substantially as shown and described.
